Patented Jan. 30, 1917

2 SHEETS--SHEET 1.

UNITED STATES PATENT OFFICE.

CHARLES IRVING PLACE, OF SHARON, CONNECTICUT.

CARBURETER.

1,214,366.

Specification of Letters Patent. Patented Jan. 30, 1917.

Application filed March 22, 1916. Serial No. 85,883.

To all whom it may concern:

Be it known that I, CHARLES IRVING PLACE, a citizen of the United States, residing at Sharon, in the county of Litchfield and State of Connecticut, have invented certain new and useful Improvements in Carbureters, of which the following is a specification.

This invention appertains to the art of carbureting devices of the type commonly employed for controlling the admission of fuel to the cylinder or cylinders of internal combustion engines. The constantly increasing cost of hydrocarbon fuels for explosive engines is so obviously detrimental to the economical operation of this class of motors as to make it a desideratum of great importance at this time to meet the need for a compact carbureting means of simple design capable of vaporizing lower grade hydrocarbons with those of the more refined class for the creation of a proper admixture to provide an economical fuel for the purposes hereinbefore referred to.

With the foregoing object in view the carbureting means of this invention has been designed and comprises a structure preferably embodying suitable supply means for supplying hydrocarbons such as gasolene, kerosene and the like to a suitable mixing chamber, previously heating the said fuel elements along with water also conducted from a suitable supply chamber whereby to obtain a mixture having the requisite combustion factor whereby to obtain a high degree of efficiency in respect to power produced incident to the explosion of the mixture in the cylinder or cylinders of an internal combustion engine.

More specifically speaking, the carbureting device of the invention comprises the usual suction valve associated with and adapted to operate suction tubes leading to the supply chambers for gasolene, kerosene (or equivalent hydrocarbons) and water, said tubes coacting with valves controlling the admission of said fuel elements to the mixing chamber.

It is contemplated to provide a heating chamber surrounding the several suction tubes and which heating chamber is heated by the exhaust products issuing from the

motor with which the carbureting device is connected, said heating chamber, furthermore, being advantageously designed with a view to heating the air adapted to be supplied to the fuel elements previously referred to, and the suction valve interiorly designed so as to control the passage of the said air from the air supply chamber into the mixing chamber. These features of the design of the carbureting device are essential and important to the invention and will be understood more fully upon reference to the aforesaid detail description, when consulted in conjunction with the accompanying drawings, in which—

Figure 1 is a view in front elevation illustrating the intake and exhaust manifolds of a conventional type of explosive engine and illustrating the carbureting device operatively arranged in respect thereto. Fig. 2 is a vertical sectional view through the carbureting device alone. Fig. 3 is a horizontal section taken about on the line 3—3 of Fig. 2. Figs. 4 to 7 inclusive are corresponding horizontal sectional views taken about on the lines 4—4, 5—5, 6—6 and 7—7 respectively of Fig. 2. Fig. 8 is a fragmentary sectional view of the exhaust pipe showing the carbon screen or baffle disposed therein. Fig. 9 is a fragmentary view bringing out more clearly the formation of the upper end of the suction tubes at the point of connection with the suction valves.

In the drawings, A denotes the intake manifold and B the exhaust manifold of a four cylinder type explosive engine, the exhaust pipe C leading from the exhaust manifold B and there being provided intermediate the parts B and C the branch exhaust pipe D containing at a suitable point in its length the baffle 1 in the form of a screen or other foraminous member the purpose of which is to prevent carbon or other foreign particles from passing into the heating chamber of the carbureting device now to be described.

The carbureting device is seen best in Fig. 2 of the drawings wherein the internal construction is clearly illustrated. Said device comprises a suitable casing 2, the upper portion of which is made in sections of somewhat rounded conformation so as to provide

the mixing chamber 3. The outlet 4 of the casing 2 is equipped with any suitable form of throttle valve 5 and mounted in the lower portion of the mixing chamber is the main or suction valve 6. The suction valve 6 is peculiar in its formation, being provided with a central guide stem 7 operating in an opening formed in a central column or post 8 located within the casing 2. Intermediate a ring 9 adjustably supported by screws 10 in the upper portion of the casing 2, and the valve 6 is located the spring 11 by which the valve 6 is normally held in a position with its periphery seated against the curved wall 15 of the mixing chamber, thereby closing the passage leading from the air chamber 12 to said mixing chamber. The air chamber 12 surrounds a heating chamber 13, the two being separated by a wall or partition 14. Disposed so as to operate in the heating chamber 13 are the suction tubes 15 the upper ends of which are joined by arms 15^a, see Fig. 9, with the valve 6, the latter having openings coinciding with the adjacent open ends of the tubes 15 and within which openings the arms 15^a are fixed. The chamber 13 is heated by means of exhaust gases supplied thereto by the branch exhaust pipe D which is coupled with the casing 2 at the inlet and outlet passages 16 and 17, respectively, these passages leading through the air chamber 12 to said heating chamber, as seen best in Figs. 2 and 5. In order that the suction tubes or conduits 15 may not be too intensely heated it is preferred that they be surrounded by the tubular members 18 to thereby establish subsidiary heating chambers 19 within which the tubes or conduits 15 are mounted and adapted to move.

The bottom of the heating chamber 13, designated 20, is supplied with apertures through which the several tubes 15 pass and project sufficiently far downward for co-operation with the needle valves 21 adapted for adjustment by the usual finger pieces 22. The parts 15 and 21 engage and coact with one another in the fuel supply chambers 23, 24 and 25, see Fig. 7, which chambers respectively are adapted to contain fuel constituents such as gasoline, kerosene and water, or any other similar or equivalent constituents such as have been found practicable for use for explosive purposes in connection with the efficient operation of internal combustion engines. The several supply chambers 23, 24 and 25 are separated by partitions 26 and said chambers are in communication with the float chambers 27, 28 and 29 respectively.

The passage of the fuel constituents from the respective chambers 27, 28 and 29 to the associated supply chambers is controlled by suitable valves 30, see Fig. 7, and these valves 30 may be so manipulated and adjusted as to vary the proportion of the fuel constituents

which may pass from the float chambers to the supply chambers, the richness of the mixture formed in the mixing chamber 3 being controllable in this manner as well as by a suitable adjustment of the needle valves 21. It is well known that under certain conditions of motor operation the amount of gasoline desired for the explosive mixture formed in the chamber 3 will be greater than under other conditions and a similar variation in the quantity of the other fuel constituents is desirable, governed by the particular conditions stated.

With each of the float chambers 27, 28 and 29 will be connected suitable supply pipes 32 for the respective fuel constituents conducted to said chambers, and any conventional type of float 33 will be located in each of these float chambers.

To afford a most suitable mounting for the valve 6, the latter is provided with a pendent annular flange 6^a adapted to surround and fit over the upper end of the chamber 13 formed by the head 31 and the partition or wall 14, any tendency for vibration of the valve or inaccurate seating action being avoided in this manner.

With the foregoing understanding of the construction of the carbureting device, the practical operation of the same may be briefly set forth as follows: The lower end of the air chamber 12 being open to the atmosphere as seen in Fig. 2, it will be understood that upon opening of the valve 6 by the suction pull of the engine said valve by its opening movement will carry the suction tubes 15 upward and permit of the passage of the fuel constituents from the supply chambers 23, 24 and 25 through said tubes to the mixing chamber 3. Coincident with the action of the valve 6 to admit the fuel to the chamber 3, is the movement of the valve to permit the air to be drawn into and through the air chamber 12 into the chamber 3, the fuel constituents and air being thus thoroughly admixed previous to introduction of the same into the engine cylinders through the intake manifold A. The fresh air drawn into and passing through the chamber 12 is, of course, heated by the wall or partition 14 between the chamber 12 and the chamber 13 and in like manner the fuel constituents are heated owing to the fact that the tubes 15 will be kept warm by the heat of the exhaust gases passing as they do through the chamber 13 and freely circulating around the tubular members 18. It is preferred that the upper end of the chamber 13 shall be closed by a head 31 which head of course has openings at the points where the parts 18 connect therewith.

While the general formation and assemblage of the parts of the carbureting device is preferably as disclosed in the drawings and set forth in the preceding description,

it is to be understood that I do not wish to be restricted thereto since the same may be modified in accordance with the spirit of my invention and the scope of the claims 5 annexed hereto.

In respect to the provision made for the admission of atmospheric air to the chamber 12, it is notable that air admission ports 12' are employed for this purpose, the same 10 being seen in Fig. 2 and being located just opposite the exhaust inlet and outlet passages 16 and 17, respectively. This arrangement is extremely advantageous in that it insures the heating of the air entering the 15 chamber 12 correspondingly facilitating the heating of the walls of the chamber in an obvious manner.

Since it is desirable when starting the motor, when the latter is cold, to entirely cut 20 off the supply of kerosene and water in the chambers 24 and 25, it is contemplated to provide suitable drain cocks for the last mentioned chambers through which the liquid contents may be drawn off. In the 25 starting operation also, the valves 30 establishing communication between the float chambers and the compartments 24 and 25 for the kerosene and water respectively, may be closed, depending of course upon the peculiar conditions involved.

The entire construction and arrangement 30 of the parts of the invention as hereinbefore set forth is conducive particularly to the utilization of the exhaust gases for heating purposes in effecting thorough carburation and vaporization of the fuel preliminary to its passage to the engine cylinders. Furthermore, the relation of the several supply compartments 23, 24 and 25, the suction tubes 15, and the float chambers 28, 40 with the controlling valves is such as to afford a most desirable and necessary range of adjustment of controlling device whereby to secure the best admixture of the hydrocarbons and water and air for the particular 45 working conditions under which the motor may be used, it being well known that such conditions vary largely according to the variations in temperature and in view of 50 the condition of the engine itself. For this reason a very considerable economy in the utilization of the fuel constituents may be practised, for obviously it is a desideratum to employ as little of the gasoline or most 55 refined and explosive hydrocarbon, as possible so that a saving in the cost of operation of the motor may be effected.

It will be observed that at their upper ends 60 the suction tubes 15 are separated from the tubes 18 and it is to be understood that any partially vaporized fuel which might have a tendency to overflow the suction tubes will be drawn into the pockets between said tubes and the tubes 18. Since the space between the above parts is heated to a higher 65

temperature than the suction tube by reason of the positions of the tubes 18 in relation to the source of heat, such overflowing fuel will be vaporized instantly and drawn into the mixing chamber. The overflowing action is permitted by the arms 15* connecting the parts 15 with the main valve. 70

Having thus described the invention, what is claimed is:—

1. In a carbureter, a casing provided with 75 a mixing chamber and formed with concentrically disposed outer and inner air and heating chambers respectively, fuel supply means passing through the heating chamber and communicating with the mixing chamber, and a main valve operating in the mixing chamber so as to control the admission of air from the air chamber to the mixing chamber and connected with the fuel supply means to control the passage of fuel 80 therefrom to the mixing chamber.

2. In a carbureter, a casing provided with 85 a mixing chamber and formed with concentrically disposed outer and inner air and heating chambers respectively, fuel supply means passing through the heating chamber and communicating with the mixing chamber, and a main valve operating in the mixing chamber so as to control the admission of air from the air chamber to the mixing chamber and connected with the fuel supply 90 means to control the passage of fuel therefrom to the mixing chamber, the fuel supply means comprising tubes connected with said valve and operable thereby to control the supply of the fuel to the mixing chamber. 95

3. In a carbureter, a casing provided with 100 a mixing chamber and formed with concentrically disposed outer and inner air and heating chambers respectively, fuel supply means passing through the heating chamber and communicating with the mixing chamber, a main valve operating in the mixing chamber so as to control the admission of air from the air chamber to the mixing chamber and connected with the fuel supply 105 means to control the passage of fuel therefrom to the mixing chamber, the fuel supply means comprising tubes connected with said valve and operable thereby to control the supply of the fuel to the mixing chamber, and means to supply a heating medium to the said heating chamber and passing 110 through the air chamber. 115

4. In a carbureter, a casing provided with 120 a mixing chamber and divided into inner and outer heating and air chambers respectively, the latter having an air supply opening and being separated from the heating chamber by a partition, means for supplying a heating medium to the heating chamber whereby to heat said partition and thereby heat the air passing through the air chamber, a valve controlling the admission 125 130

of air to the mixing chamber from the air chamber, and fuel supply means controlled by said valve and adapted to be heated by said heating chamber.

5. In a carbureter, a casing provided with a mixing chamber and divided into inner and outer heating and air chambers respectively, the latter having an air supply opening and being separated from the heating chamber by a partition, means for supplying a heating medium to the heating chamber whereby to heat said partition and thereby heat the air passing through the air chamber, a valve controlling the admission 10 of air to the mixing chamber from the air chamber, fuel supply tubes connected with said valve and passing through the heating chamber, and other valve means coacting with said tubes and the action of which in 15 coöperation with the tubes is governed by the movement of the first mentioned valve.
6. In a carbureter, a casing provided with a mixing chamber and divided into inner and outer heating and air chambers respectively, the latter having an air supply opening and being separated from the heating chamber by a partition, means for supplying a heating medium to the heating chamber whereby to heat said partition and thereby 20 heat the air passing through the air chamber, a valve controlling the admission of air to the mixing chamber from the air chamber, fuel supply tubes connected with said valve and passing through the heating chamber, other valve means coacting with said tubes and the action of which in 25 coöperation with the tubes is governed by the movement of the first mentioned valve, and tubular members disposed in the heating chamber 30 surrounding said tubes to prevent direct action of the heat in said chamber upon the tubes.

7. A carbureter comprising a casing having at its upper portion a mixing chamber and at its lower portion concentric air and heating chambers, the latter disposed within the air chamber and separated therefrom by a partition, a valve mounted in the mixing chamber and normally closing the space between the heating and air chambers, and shutting off communication between the air chamber and the mixing chamber, and fuel supply means for conducting fuel constituents through the heating chamber into the mixing chamber and controlled in action by said valve.

8. A carbureter comprising a casing having at its upper portion a mixing chamber and at its lower portion concentric air and heating chambers, the latter disposed within the air chamber and separated therefrom by a partition, a valve mounted in the mixing chamber and normally closing the space between the heating and air chambers and 60 shutting off communication between the air 65

chamber and the mixing chamber, fuel supply tubes connected with said valve and movable thereby through the heating chamber, and other valves coacting with the said tubes and governed in their coaction by the movement of the tubes with the first named valve.

9. A carbureter comprising a casing having at its upper portion a mixing chamber and at its lower portion concentric air and heating chambers, the latter disposed within the air chamber and separated therefrom by a partition, a valve mounted in the mixing chamber and normally closing the space between the heating and air chambers and 75 shutting off communication between the air chamber and the mixing chamber, and fuel supply tubes connected with said valve and in communication with the mixing chamber, said tubes passing through opposite ends of 80 the heating chamber and being movable by said valve, other valves adapted to close the inlet ends of said tubes and governed in their action by the movement of the tubes relatively thereto incident to the movement of 85 the first named valves.

10. A carbureter comprising a casing having at its upper portion a mixing chamber and at its lower portion concentric air and heating chambers, the latter disposed within 90 the air chamber and separated therefrom by a partition, a valve mounted in the mixing chamber and normally closing the space between the heating and air chambers and shutting off communication between the air 95 chamber and the mixing chamber, fuel supply tubes connected with said valve and in communication with the mixing chamber, said tubes being movable by said valve, and other valves adapted to close the inlet ends 100 of said tubes and governed in their action by the movement of the tubes relatively 105 thereto incident to the movement of the first named valves, the said casing being formed with separate fuel supply chambers each 110 adapted to communicate with a respective tube and governed in said communication by one of the last mentioned valves.

11. A carbureter comprising a casing having at its upper end a mixing chamber and 115 its lower portion divided into upper and outer heating chambers respectively, the latter having an air inlet opening, a valve disposed in the mixing chamber and arranged to cut off communication between said chamber and the air chamber, fuel conducting tubes connected with said valve and passing through the heating chamber, the casing being divided at its lower portion into fuel supply chambers communicating with the 120 lower ends of said tubes, valves in said supply chambers adapted to close the lower ends of the tubes until the latter are opened by the movement of the tubes with the first 125 mentioned valve, the casing having a heat 130

conducting passage leading through the air chamber and communicating with the heating chamber.

12. A carbureter comprising a casing having at its upper end a mixing chamber and its lower portion divided into upper and outer heating chambers respectively, the latter having an air inlet opening, a valve disposed in the mixing chamber and arranged to cut off communication between said chamber and the air chamber, fuel conducting tubes connected with said valve and passing through the heating chamber, the casing being divided at its lower portion into fuel supply chambers communicating with the lower ends of said tubes, valves in said supply chambers adapted to close the lower ends of the tubes until the latter are opened by the movement of the tubes with the first mentioned valve, the casing having a heat conducting passage leading through the air chamber and communicating with the heating chamber, a spring disposed in the mixing chamber and engaging the first named valve to normally hold the same in a position closing communication between the air and mixing chambers, a ring connected with said spring, and means to adjust said ring to vary the tension of the spring.

13. A carbureter comprising a casing having at its upper end a mixing chamber and provided at its lower end with separate fuel supply chambers and intermediate said mixing and fuel supply chambers formed with inner and outer heating and air chambers respectively, one surrounding the other, a valve controlling the admission of air to the mixing chamber from the air chamber, fuel conducting tubes leading from the fuel supply chambers through the heating chamber to the mixing chamber, and means governed by said valve for controlling the admission of fuel to the mixing chamber through said tubes.

14. A carbureter comprising a casing having at its upper end a mixing chamber and provided at its lower end with separate fuel supply chambers and intermediate said mixing and fuel supply chambers formed with inner and outer heating and air chambers respectively, one surrounding the other, a valve controlling the admission of air to the mixing chamber from the air chamber, fuel conducting tubes leading from the fuel sup-

ply chambers through the heating chamber to the mixing chamber, and means governed by said valve for controlling the admission of fuel to the mixing chamber through said tubes, the casing being formed with a passage for conducting the heating medium to the heating chamber whereby to heat the tubes passing through the latter and to heat air passing through the surrounding air chamber.

15. In a carbureting means of the class described, the combination of a mixing chamber, a valve for controlling admission of fuel constituents to said chamber, suction tubes and coacting valve means controlled by the first named valve and adapted to supply fuel constituents to said chamber, tubular members surrounding said suction tubes and spaced therefrom to form heating spaces about the tubes, and means to heat said tubular members and thereby correspondingly heat the suction tubes.

16. In a carbureting means of the class described, the combination of a mixing chamber, a valve for controlling admission of fuel constituents to said chamber, suction tubes and coacting valve means controlled by the first named valve and adapted to supply fuel constituents to said chamber, tubular members surrounding said suction tubes and spaced therefrom to form heating spaces about the tubes, and means to heat said tubular members and thereby correspondingly heat the suction tubes, comprising an exhaust passage for conducting exhaust gases from the motor equipped with the said carbureting means to act upon the tubular members for heating purposes.

17. In carbureting means as set forth, the combination with a casing having a mixing chamber, of fuel supply means communicating with said chamber and an air chamber also adapted to supply air to the mixing chamber, exhaust passages leading to the fuel supply means for causing heating of the latter by exhaust gases from a motor equipped with the carbureting means, said air chamber being provided with air inlet ports located proximate to said exhaust passages whereby the air drawn into the air chamber will be heated owing to such proximity of the air inlet ports and exhaust passages.

In testimony whereof I affix my signature.
CHARLES IRVING PLACE.
